W. H. WENDT

WINDER SHAFT

Filed Dec. 28, 1922

FIG. 1

FIG. 2

FIG. 4

FIG. 3

Inventor
WILLIAM H. WENDT

By Paul, Paul & Moore

Attorneys

UNITED STATES PATENT OFFICE.

WILLIAM H. WENDT, OF LITTLE FALLS, MINNESOTA.

WINDER SHAFT.

Application filed December 28, 1922. Serial No. 609,545.

To all whom it may concern:

Be it known that I, WILLIAM H. WENDT, a citizen of the United States, resident of Little Falls, county of Morrison, and State 5 of Minnesota, have invented certain new and useful Improvements in Winder Shafts, of which the following is a specification.

The object of my invention is to provide a winder shaft supporting a core on which 10 paper or other material is wound and having means for easily and quickly locking the core on the shaft or releasing it without the employment of set screws or any other device that might in any way tend to 15 increase or cause liability of injury; said locking means being removable at the ends of the shaft to allow the core with the paper or other material wound thereon to be easily removed.

20 Other objects of the invention will appear from the following detailed description.

The invention consists generally in various constructions and combinations all as 25 hereinafter described and particularly pointed out in the claims.

In the accompanying drawings forming part of this specification.

Figure 1 is a view partially in section 30 of a winder shaft embodying my invention;

Figure 2 is a sectional view on the line 2-2 of Figure 1;

Figure 3 is a detailed sectional view showing 35 the manner of mounting the locking device on the shaft;

Figure 4 is a sectional view on the line 4-4 of Figure 3.

In the drawing, 2 represents a winder shaft having the squared ends 3 for the application of a tool to revolve the shaft and tighten the lock nuts as will hereinafter appear.

4 is a core loosely encircling the shaft and on which paper or other material is 45 wound. At each end of the core, a hub 5 is provided and as these hubs and the mechanism connected therewith is the same at both ends of the shaft, I will describe one, indicating the other by the same reference 50 numerals with the addition of the exponent "a".

A hub 5 has an extension 6 thereon exteriorly threaded to receive a nut 7 that

is adapted to engage one end of the core 4, and when the other end is similarly engaged, and locked, the core will be secured against rotary movement. 55

An annular groove 8 is provided in each end of the shaft and radially arranged jaws 9 are mounted in a collar 10 and adapted 60 to move toward and from the shaft, and said jaws at their inner ends have seats 11 for contact with the bottom of the groove 8, and a pin 12 is mounted in said shaft and projects into the groove 8 in position 65 to engage the jaws and prevent rotary movement of the collar and hub except such slight movement as may be permitted by the space between the pin and the inwardly projecting ends of the jaws. The outer portions 70 of the jaws have curved recesses 13 therein to receive cams 14 projecting from a ring 15 that is seated in bearings 16 in the hub 5; said ring having holes 17 therein to receive a spanner wrench—not shown—when 75 it is desired to rotate the ring and move the locking jaws. Evidently rotary movement of the ring in one direction will project the jaws inwardly to contact with the shaft, and in this position, the jaws will be in the 80 path of the pin 12 and will be locked against rotary movement independently of the shaft.

Movement of the ring in the opposite direction will withdraw the jaws from the 85 annular groove in the shaft and release the hub and allow it and the nut thereon to be withdrawn from contact with the end of the core. As long as the jaws are in their projected position, relative rotary movement of the hub and the shaft will be prevented as well as longitudinal movement thereof, but as soon as the locking jaws are retracted, a suitable tool may be applied to the end of the shaft to revolve it and release 90 the core, and then the shaft may be moved longitudinally and withdrawn entirely from the core. In the same way, the nuts can be tightened against the ends of the core by revolving the shaft and rotating the hubs 95 with it. This device provides a very substantial and convenient means for supporting a core for a roll of paper and permitting the rapid withdrawal of the shaft from the core when the roll has been completed. 100 During the winding operation, the core will 105

be securely clamped and held against independent rotary movement until the pressure on the ends is relieved.

I claim as my invention:

1. A device of the class described comprising a shaft, a core thereon, a hub loosely mounted on said shaft, an adjustable nut thereon having an end friction surface for engaging and clamping a corresponding end 10 surface of said core, a stop for the opposite end of said core, means for locking said hub against rotary and longitudinal movement on said shaft, said core being held by frictional engagement with said stop and nut.
- 15 2. A device of the class described comprising a shaft, a core thereon, a hub at one end of said core, a nut thereon for engaging said core, a stop against which the other end of said core is seated, a collar mounted on 20 said hub, jaws mounted in said collar for engaging said hub, a ring loosely mounted on said hub and having cams thereon for engaging said jaws to project and withdraw them when said ring is rotated.
- 25 3. A device of the class described comprising a shaft having an annular groove and a pin in the bottom of said groove, a hub loosely mounted on said shaft, radially arranged jaws mounted in said hub and adapted to enter said groove, means for projecting and withdrawing said jaws, said jaws with said pin, when in their projected posi-

tion engaging said pin and, locking said hub on said shaft against rotary and longitudinal movement, a nut adjustably mounted on 35 said hub, a core carried by said shaft and engaged at one end by said nut, and means at the other end of said core against which it is clamped by the movement of said nut.

4. A device of the class described comprising a shaft, a core loosely mounted thereon, adjustable means at each end of said core having friction surfaces for engaging and clamping corresponding surfaces of said core, supports for said adjustable means, 40 and means for locking said supports on said shaft, rotation of said shaft advancing or retracting said locking means to lock or release said core.

5. A device of the class described comprising a shaft, a core loosely mounted thereon, hubs provided at each end of said core on said shaft and having adjustable nuts thereon provided with friction surfaces for engaging the ends of said core and clamping 55 it against rotary movement, and means for locking said hubs against rotary and longitudinal movement, the revolution of said shaft when said hubs are locked thereon operating to tighten said nuts against said core.

In witness whereof, I have hereunto set my hand this 23rd day of December, 1922.

WILLIAM H. WENDT.
